United States Patent Office

Des. 202,466

Patented Oct. 5, 1965

202,466
VACUUM OVEN HOUSING OR SIMILAR ARTICLE
 Clifton E. Hayes, Concord, N.H., assignor to Richard
 D. Brew and Company, Inc., Concord, N.H., a corpora-
 tion of New Hampshire
 Filed Oct. 1, 1964, Ser. No. 81,985
 Term of patent 14 years
 (Cl. D16—2)

FIG. 1

FIG. 2

FIGURE 1 is a perspective view of a vacuum oven housing showing my new design; and

FIGURE 2 is an end view thereof.

The undisclosed rear portion of the housing is flat and plain.

The broken lines are shown for illustrative purposes only.

I claim:

The ornamental design for a vacuum oven housing or similar article, substantially as shown and described.
